UNITED STATES PATENT OFFICE

2,446,053

ADJUSTABLE CAP

Stephen Matarazzo, Schenectady, N. Y.

Application November 16, 1946, Serial No. 710,372

4 Claims. (Cl. 2—197)

1

My invention relates to an adjustable cap, and more specifically to a cap comprising concealed band-adjusting means in back for adjusting the size of the cap. My invention additionally relates to improved means for adjusting the head size of a cap.

An object of my invention is to provide a cap of improved construction wherein the head size of the cap may be readily adjusted to fit the wearer. A further object of my invention is to provide an adjustable headband for a cap, the adjusting means being so arranged as to be unnoticeable, yet readily exposable for adjustment.

The novel features which I believe to be characteristic of my invention are set forth with particularity in the appended claims. My invention itself, however, both as to its organization and method of operation, together with further objects and advantages thereof may best be understood by reference to the following description taken in connection with the accompanying drawings wherein Fig. 1 is a view of a cap incorporating the invention showing the general appearance of a preferred embodiment; Fig. 2 is a view of a cap showing the details of a removable visor; Fig. 3 is a rear view of a cap showing means for adjusting the size of the cap; and Fig. 4 is a view showing modified adjusting means applicable to the rear of the cap of Fig. 3.

Referring now to the drawings, Fig. 1 shows a cap embodying my invention as it appears when ready for use, the cap comprising a crown 1, formed from two pieces of fabric or other material joined by a preferably welted, felled, or bound seam 2. Band 3 is stitched to the base of the crown as later described. Visor 4 is suitably bound along the edge and is attached to band 3 as best shown in Fig. 2. A row of female snap fastener members 5 is provided along curved upstanding flange 6 formed along, or secured to, the inner edge of visor 4. The flange is adapted to fit under band 3 along the front of the cap, female members 5 being arranged for cooperation with male snap fastener members 7 provided along the inner face of the band. For purposes of illustration, a portion of the band is cut and rolled back in Fig. 2 to show one of the male snap fastener members 7. Only the upper edge of the band is stitched to crown 1 across the front of the cap to permit insertion of flange 6 under the band. For the remainder of its length, the band is stitched to the crown along both the top and bottom edges, which may

2

be bound or rolled as shown in the turned-back portion visible in Fig. 2.

Referring now to Fig. 3, a strap member 8 is secured at or near its two extremities to the outer surface of band 3 a short distance from the overlapping end portion of the band, and to the inner surface a short distance from the other underlying end. Stop member 9, which is preferably buckle-like in form, is adjustably positioned on strap 8 and is provided with male snap fastener members 10 for cooperation with female members 11 attached to the underside of band 3 adjacent the outer end portion 12, near which strap 8 is attached to the underside of the band. When fastened down to the stop member 9, the end portion 12 serves to completely hide the stop member and the greater part of strap 8 from view. Adjustments to adapt the cap for a desired head size are accomplished by sliding member 9 along strap 8, the member 9 being readily exposed for adjustment by detaching from the stop member and rolling back end portion 12 into the position shown in Fig. 3. Since strap 8 is secured at both ends to band 3, the stop member cannot be removed from the strap.

A slit 13 is shown in the back portion of crown 1 adjacent the ends of band 3, providing a latitude permitting adjustments of the cap size within wide limits. The edges of the slit are preferably hemmed as shown in Fig. 3.

Fig. 4 shows a modified construction of the size adjusting means wherein the stop member 9 has no snap fastener members. The end portion 12 of band 3 carries a split ring 14 arranged to slip over strap 8 beyond stop member 9. The stop member, in cooperation with ring 14 and end portion 12 of band 3, thus determines the head size of the cap. The shape and dimensions of ring 14 are so arranged that it will not pass over the stop member. The ring may be of relatively stiff material and formed as shown so as to be slideably positionable onto strap 8, or it may be of a spring-like or soft deformable metal, plastic, or other material and may normally form a closed ring with a slit or joint so arranged as to permit fastening around or removal from the strap. As indicated in the drawing, the ring is preferably flattened and when in operative position on the strap, serves to so position end portion 12 of band 3 as to cover and conceal the stop member.

If the cap is to be cleaned or washed, visor 4 is removed, and, if desired, the ring 14 is slipped off of strap 8 and slipped out of the loop provided in the end of band 3. As pointed out above, stop member 9 cannot be removed from strap 8 un-

less the strap is cut away from band 3 at one end.

The crown, band and visor of the cap may be of fabric, leather or other suitable material, and may be pliable or stiffened. The visor may be provided with a polished surface, and may be of different material from the crown. My invention is adaptable for use in military, naval or other uniform caps. In addition to being washable, use of the cap obviates the necessity of stocking caps of different sizes to supply persons of widely varying head sizes. While no sweat band is shown in the drawings, it is contemplated that a sweat band of any known type desired may be provided, it being necessary only that such band be not joined into a continuous band at the back of the cap, since allowance should be made for adjustments to the head size of the cap without wrinkling or stretching the sweat band.

While I have shown only certain preferred embodiments of my invention by way of illustration, many modifications will occur to those skilled in the art and I therefore wish to have it understood that I intend, in the appended claims, to cover all such modifications as fall within the true spirit and scope of my invention.

What I claim as new and desire to secure by Letters Patent of the United States is:

1. A cap comprising a crown, a band attached along the periphery of said crown, said band having two ends at the back of said cap, one of said ends being adapted to overlap the other end, a strap with two extremities attached respectively to the inner side of said band adjacent said one end and to the outer side of said band adjacent said other end, a stop member slidably arranged on said strap, and means adjacent said one end of said band for cooperation with said stop member to confine said band to a predetermined effective length and to cause a portion of said band to conceal said stop member.

2. In a cap, a band, a crown attached to said band, said band having overlapping end portions at the back of said cap, a strap interposed between said end portions of said band, said strap having two extremities each attached to said band respec-

tively adjacent said end portions thereof, a stop member adjustably arranged on said strap, and means for locking the outer one of said end portions in covering position over said stop member, 5 said means cooperating with said stop member and said outer one of said end portions to determine the head size of said cap.

3. In a cap, a band, a crown attached to said band, said band having overlapping end portions 10 at the back of said cap, a strap interposed between said end portions of said band, said strap having two extremities each attached to said band respectively adjacent said end portions thereof, a stop member adjustably arranged on said strap, and 15 a member attached to the outer one of said end portions cooperating with said strap to maintain said outer end portion in covering relationship with said stop member and cooperating with said stop member to determine the head size of said cap.

4. In a cap, a band, a crown attached to said band, said band having overlapping end portions at the back of said cap, a strap interposed between 20 said end portions of said band, said strap having two extremities each attached to said band respectively adjacent said end portions thereof, a stop member adjustably arranged on said strap, and 25 means associated with said stop member and with the outer one of said end portions to maintain said outer end portion in predetermined relative 30 covering position with respect to said stop member and to determine the head size of said cap.

STEPHEN MATARAZZO.
